UNITED STATES PATENT OFFICE.

FRANCIS M. HESS, OF CHICAGO, ILLINOIS.

METHOD OF AND APPARATUS FOR EFFECTING CONTINUOUS DISTILLATION.

Application filed May 8, 1919. Serial No. 295,527.

To all whom it may concern:

Be it known that I, FRANCIS M. HESS, a citizen of the United States, residing at Chicago, in the county of Cook and State 5 of Illinois, have invented certain new and useful Improvements in Methods of and Apparatus for Effecting Continuous Distillation, of which the following is a specification.

10 This invention relates to a new and improved method of, and apparatus for, effecting the continuous distillation of hydrocarbon materials such as coal tar and petroleum, and their distillates. A long felt want in 15 continuous distillation systems has been for one that will not only release the vapors formed, and in turn condense them, before they rise too far above their own vaporizing points, but that will also afford a desirable 20 transfer of latent heat from the products fractionated to the materials in process of heating.

The objection to raising the temperatures of the vapors too far above their own vaporizing points lies in the fact that they will 25 either become permanent gases that are hard to condense, or they will unite with other gases of higher vaporizing points and form undesirable distillate products.

30 It is necessary, therefore, in planning a desirable routing scheme for liquids undergoing distillation, to provide one that will not only afford an ideal heat transfer system but will also release and condense the 35 vapors as fast as they are formed.

With these desirable objects in view, I have evolved the method and apparatus for effecting continuous fractional distillation forming the subject matter of this invention; 40 and I will now proceed to a detailed description of the same in connection with the accompanying drawings wherein I have illustrated one practical and efficient form of apparatus in which the mechanical features of the invention may be embodied, and by the use of which my novel method or a 45 process of distillation may be carried out.

I may here remark that the present invention has been so designed as to preferably, 50 although not exclusively, make use of superheated steam as a heating agent in the boilers or vapor boxes of the system; and in the apparatus herein disclosed I have illustrated a heating equipment adapted to the 55 use of superheated steam, although it should be understood that in the broader aspects of

the invention the use of superheated steam is optional and not essential.

Referring to the drawings,—

Fig. 1 is a diagrammatic view of a complete distillation plant embodying my invention;

Fig. 2 is a similar view as seen from the right of Fig. 1, the heat exchangers being omitted for the sake of clearness;

Fig. 3 is an enlarged vertical section through one of the vapor boxes;

Fig. 4 is a horizontal section on the offset line 4—4 of Fig. 3;

Fig. 5 is a vertical section through one 70 of the heat exchangers;

Fig. 6 is a longitudinal section through one of the vapor condensers;

Fig. 7 is an enlarged cross-section through 75 one of the vapor condensers;

Fig. 8 is a front elevation, partly in longitudinal vertical section, of the overflow trough of the vapor box;

Fig. 9 shows a modified form of heating 80 plate.

Referring first to Figs. 1 and 2, A, A', A² and A³ represent a series of vapor boxes in which the material treated is subjected to heat for the purpose of driving off the distillates which are released at different temperatures. B, B', B² and B³ represent a series 85 of condensers that are connected by pipes C, C', C² and C³ with the respective vapor-boxes; each condenser, as herein shown, comprising a group of three condensing 90 units connected in series by pipes c.

D, D', D² and D³ indicate a corresponding series of heat exchangers which are interposed in alternating relation between a leveling tank E and the first vapor-box A and 95 between the remaining vapor-boxes of the series, by means of inflow and outflow pipes F, F', F² and G, G', G² and G³, respectively. H designates a residuum tank connected with the bottom of the lowermost 100 vapor-box A³ by a pipe I. K indicates a residuum pump that is connected on its intake side through pipe L with the residuum tank H and on its discharge side through pipe M with the bottom of the lowermost 105 D³ of the series of heat exchangers; it being here noted that the heat exchangers are superposed on each other and connected top to bottom by short pipe lengths N. From the top of the uppermost heat exchanger D 110 a discharge pipe O conducts the residuum to any suitable or desired place of delivery.

P designates the discharge pipe from the first condenser B; P' designates the discharge pipe from the second condenser B'; P² designates the discharge pipe from the 5 third condenser B²; and P³ designates the discharge pipe from the fourth or last condenser B³.

Q designates a pipe constituting in part the supply line for the crude material drawn 10 from any convenient source. This pipe leads into one end of the lowermost of the group of condenser units B; a convenient form of condenser unit being illustrated in Figs. 6 and 7, and consisting of a drum 10 having hollow heads 11 and 12 connected by tubes 13. 14 and 15 designate a pair of baffle plates extending in opposite directions from the inner walls of the hollow heads 12 and 11, respectively, nearly but not 15 quite to the opposite end, thereby producing a zigzag route or passageway for the vapors while undergoing condensation, the vapors entering at the top by the pipe C, C', C² or C³, passing from each unit of the group 20 to the next through connecting pipes c and passing off through pipe P, P', P² or P³ to its point of collection.

The supply line from the pipe Q continues through the hollow head 11, the tubes 30 13, the hollow head 12, and the connecting tube q to the next condenser unit of the group, thence through another connecting tube q to the topmost unit of the group, thence through a connecting pipe Q' to the 35 lowermost of the group of condensers B', through these and connecting pipe Q² to and through the next group of condensers B², thence through connecting pipe Q³ to and through the lowermost group of condensers B³; thence by pipe Q⁴ into the upper 40 end of the leveling tank E. From the latter the material flows by gravity alternately through the heat exchangers and the vapor-boxes, passing first through the uppermost 45 heat exchanger D, thence through vapor-box A, where the most volatile vapors are driven off, thence through heat exchanger D', thence through the second vapor-box A' where the next most volatile products are 50 driven off, thence through the third heat exchanger D² and thence through the third vapor-box A² where the still heavier vapors are driven off, thence through the last heat exchanger D³, and finally through the fourth 55 or last vapor-box A³. Fig. 5 illustrates in vertical section a preferred form of heat exchanger consisting simply of a vertical drum 16 having lower and upper hollow heads 17 and 18 and a series of straight 60 connecting tubes 19 between said heads. From the lowermost vapor-box the residuum flows through pipe I into the residuum tank H where, in a highly heated condition, it is forced by the pump K upwardly through 65 the series of heat exchangers D³, D², D'

and D, passing through them successively in the order named. As the material treated flows from the leveling tank to the first vapor-box and from each vapor-box to the next through one of these heat exchangers, it picks up a large amount of latent heat in the residuum, carrying it on into the next vapor-box and to that extent utilizing heat that would otherwise pass off and be wasted with the residuum.

Similarly, the passage of the cold crude material through the condensers has the double advantage of condensing the vapors and transferring the latent heat of the latter to the crude material, so that by the time 80 the latter reaches the leveling tank it has absorbed a large amount of heat.

It will be understood that any desired number of units, whether of vapor-boxes, condensers or heat exchangers, may be employed in the system, and the crude material may pass through any or all of the condensers or through any or all of the heat exchangers as may be found desirable or necessary in practice.

In Figs. 3 and 4 I have illustrated somewhat in detail desirable structural characteristics of the boiler or vapor-box. As herein shown, this comprises an outer rectangular box-like housing or casing consisting of stationary top and bottom walls 20 and 21, stationary opposed side walls 22, and laterally removable opposed side walls 23 which are normally united to the side walls 22 by angle beams 24 and bolts 25. Within this 95 casing or housing is a zigzag conduit for the flow of the material to be distilled through the vapor-box. This conduit is made up of hollow flat inclined plates or walls 26 and 27 that are connected at their 100 proximate ends by curved walls 26' and 27', respectively, of the same hollow formation. Each complete series of walls 26 and 27 is of zigzag or W-form, the two series being internested and the zigzag conduit for the 105 flow of the material to be distilled being between them. These walls may be cellular castings as indicated in Fig. 4, or, as indicated in Fig. 9, they may consist of steel plates 28 united at intervals by rivets 29 so 110 as to provide a structure capable of resisting the internal pressure of the superheated steam flowing therethrough. The lower and upper walls 27 are provided with leads 30 and 31 extending through one of the side 115 walls 23, and the lower and upper walls 26 are provided with similar leads 32 and 33 extending through the opposite side wall 23, these leads on adjacent vapor-boxes 120 united by connections 34, so that the hollow 125 steam conducting walls of the conduits of the several vapor-boxes are continuous from bottom to top throughout the entire series.

The walls 26 and 27 within the housing 130 are supported on vertical frame structures

35 and 36, respectively, at each side, the two pairs of frames being connected by tie-rods 37 on which the inclined walls 26 and 27 rest, as clearly shown in Fig. 3. On the 5 lower ends of the frames 35 and 36 are wheels 38 traveling on a pair of rails 39 forming a track-way. At one upper corner of the housing is an over-flow trough 40 (Fig. 8) preferably formed with a serrated 10 upper edge 40' on its front wall to distribute the material, into which trough the material is first introduced and from which it overflows onto the broad inclined top wall or plate 26 of the conduit, dropping from the 15 end of the latter onto the topmost wall 27, flowing in a broad, wide stream down and off the lower end of the latter onto the next wall 26 and so on to the bottom of the vapor-box; being discharged from the latter 20 into the lead to the heat exchanger or directly into the residuum tank, as the case may be. Superheated steam flows counter-current through these hollow walls, thereby rapidly and effectively heating the material 25 and releasing the vapors as soon as the vaporizing temperatures of the latter are reached in the course of the material. Of course, the topmost vapor-box is the coolest of the series and the lowermost vapor-box 30 is the hottest, so that the most easily formed vapors pass off from the topmost vapor-box while those forming at higher temperatures are discharged from the lower vapor-boxes.

Whenever it becomes necessary to disassemble one of the boilers or vapor-boxes, this is very easily done by disconnecting the 35 connections 34, removing certain of the bolts 25 at the corners of the structure, and then drawing the side walls 23 with the conduit 40 wall and their supports laterally apart.

As hereinbefore stated, the heating element preferably used herein is superheated steam. This affords a gaseous heating medium that is easy to regulate to any desirable 45 temperature; it is also positive in its action; its temperature can be varied on short notice; it heats the liquid in all parts of the vapor-box uniformly, and no hotter than desired; it can be operated at any desired 50 pressure; and by running the superheated steam counter-current to the flow of the liquid through the vapor-box the liquid is constantly increasing in temperature; and by running the heating medium upwardly 55 from vapor-box to vapor-box in a direction opposite to the flow of the liquid, the latter is heated in desirable successive steps. In a word, there is nothing desirable in operation or control that is not possible of attainment with the use of superheated steam as the heating agent.

The described construction of boiler or vapor box affords the following advantages. The material heated is kept constantly in motion, and by arranging the vapor-boxes

one above another the material flows by its own gravity in a downward course through the several boxes, thus affording a constant pressure. In flowing in a broad thin stream over the heated plates of the zigzag conduit 70 it is most advantageously and uniformly subjected to the heat of the heating medium, and in falling from plate to plate it is successively atomized to release vapors. There is ample space between the edges of 75 the plates and the walls of the casing or housing to allow the vapors to immediately rise and pass off through the vapor line; and the construction of the vapor-boxes is such that the entire structure may be disassembled for repairs and cleaning, when necessary, with a minimum of time and labor. Furthermore, with the described construction of vapor-box, and the material kept constantly in motion, the nuisance of 80 carbon deposits in the bottom is eliminated. The specific structure of this vapor box or still is not claimed herein, but forms the subject matter of a divisional application filed February 17, 1921, Serial No. 445,619, 85 which application was allowed July 12, 1922.

The heat exchangers are preferably of the one-pass type shown, to prevent the residuum from becoming pocketed and plugging the orifices. The units are preferably set one upon another as shown in such fashion that they are all constantly full and the residuum is constantly in motion in an upward direction. Preferably 100 the heat exchanger units are so disposed relatively to the vapor-boxes that the material in passing from box to box must flow through the units of the heat exchangers in its downward direction, thus successively 105 taking the heat from the residuum, the heat transfer thus being made at the most desirable points.

The type of condenser herein shown for the distillate products is not essential, but 110 is well adapted to take the heat from the vapors as fast as they come over and is so constructed as to allow the crude material to absorb this heat on its way to the leveling tank and vapor-boxes. Of course, one 115 or more condensers may be used for each vapor-box, as desired. Preferably, and as shown, the condensers are so constructed that the crude material will always be traveling in an opposite direction to that of the 120 vapors.

I do not confine the invention to the exact routing of materials shown in the drawings. The construction being based on the multiple principle I may employ as many or as few vapor-boxes as desired. In turn this will determine how many heat exchangers and condensers are to be in service. The routing of the crude material through the several condensers is controlled by the tem- 130

perature to which the final residuum is heated. In cases where this is extremely high it will be found that the crude material will be heated too high by going through all 5 the condensers before reaching the leveling tank. This would necessitate re-routing to suit the residuum temperature acquired and also the temperature desired at the first vapor-box.

10 The system is also such that several residuums of different consistencies may obviously be taken off at the same time if desired.

15 It is also noted that the system may be operated with the vapors coming from the vapor-box under the pressure caused by the gravity of the material; it may be operated with a partial vacuum in the vapor line; or it may be operated with a pressure greater 20 than that caused by the gravity of the material.

The arrangement is such that, regardless of what pressure the system is operated under, the material is traveling from vapor-box to vapor-box in successive steps, heat being transferred from condensers, exchangers and plates of the vapor-box in the proper sequence of degrees of heat. With the continued rise of temperature of the material, 25 the vapors evolved at different temperatures pass over into the vapor line and through the condensers. This not only affords a practice producing results almost identical with the best results obtained in the old style 30 still, when properly operated, as far as fractionating of distillates is concerned, but in addition the process is continuous, no part of the material being over heated and causing 35 improper cracking. There is an almost 40 equal transfer of heat from the fractionated products to the crude material, and the loss in distillation is practically negligible. In addition to distilling with a minimum fuel and labor cost, the resulting products are 45 far superior, and the fire hazard and accident features are reduced to a minimum. The superheated steam never comes in direct contact with any of the materials during

the process of distillation, so that the addition of moisture to the distillates, that in 50 many cases is hard to extract, is avoided.

I claim:

1. In a method of effecting continuous distillation, the steps or operations which consist in causing the fractional distillates to flow 55 from a series of vapor-boxes through a corresponding series of condensers, causing the crude material to flow through the said condensers out of contact with said distillates successively from the coolest to the hottest of 60 said condensers, causing the crude material to flow from the last of said condensers alternately through the units of said series of vapor-boxes and a series of heat exchangers from the coolest to the hottest, and causing 65 the residuum from the last of said vapor-boxes to flow successively through said heat exchangers.

2. In an apparatus for effecting continuous distillation, the combination of a series 70 of vapor-boxes, a series of condensers connected to the respective vapor-boxes, a supply line for the crude material leading through said condensers into the first of said vapor-boxes, a series of heat exchangers 75 interposed in alternating relation between and connected into said vapor-boxes, and a discharge line for the residuum leading from the last of said vapor-boxes through said heat exchangers.

3. In an apparatus for effecting continuous distillation, the combination of a series of vapor-boxes arranged to permit a gravity flow of the crude material successively therethrough, a series of condensers connected to 85 the respective vapor-boxes, a supply line for the crude material leading through said condensers into the highest of said vapor-boxes, a series of heat exchangers interposed in alternating relation between and connected 90 into said vapor-boxes, and a discharge line for the residuum leading from the lowest of said vapor-boxes through said heat exchangers.

FRANCIS M. HESS.
